Inventor

C. D. Olmstead.

United States Patent Office.

C. D. OLMSTEAD, OF WILLIAMSPORT, PENNSYLVANIA.

Letters Patent No. 73,031, dated January 7, 1868.

IMPROVEMENT IN SAW-MILLS.

The Schedule referred to in these Letters Patent and making part of the same.

TO ALL WHOM IT MAY CONCERN:

Be it known that I, C. D. OLMSTEAD, of Williamsport, Lycoming county, and State of Pennsylvania, have invented a new and improved Muley-Saw Hanging; and I do hereby declare that the following is a full and exact description thereof, reference being had to the accompanying drawings, and to the letters of reference marked thereon.

The nature of my invention consists in a simple means of adjusting perfectly a saw, and regulating the range of the same by means of a suitable cross-head and muley.

To enable others skilled in the art to make and use my invention, I will proceed to describe its construction and operation.

A A, Figure 1, show stationary framework, of an ordinary character, seen in all saw-mills, for the purpose of restraining the machinery used, and which is constructed as may be required. B is a stationary column, firmly fastened to the framework A. C is a plank, convex on its posterior surface, and held fast to the stationary column B by suitable screws or bolts. *c' c''* are wedges placed under the edges of the convex plank, of sufficient size to make the surface straight, and which wedges can be driven on either side, changing the range of the saw as may be deemed important. *d' d''* are hooks, firmly fastened to the convex plank C, to hold the muley to its place, and, extending into a step, made for the purpose, allows the muley to slide up and down. D is the back part of the muley proper, and in which the stop or rabbet is cut, to receive the hooks *d' d''*. E is the front guide, attached by lugs P P to the back part D, as shown clearly in Figure 5, in which figure the opening to receive the saw is also seen. F F, Figures 3 and 4, are the shuttle-blocks, fastened to the saw by a single bolt. The shuttle plays in the space between the front guide E and the back part of the muley D, which space is denoted by *z*, fig. 5. *e* is a steady-plate, attached to the front guide E, and extending also to the back part D, and protects the lower end of the muley. G is an ordinary hand-wheel, having a rack and pinion, in the usual manner in which such appliances are constructed, for the purpose of elevating or depressing the muley as desired. The lugs P P, by which the front guide is fastened, are slotted, as seen in figs. 1, 2, and 5, for the purpose of adjusting the front guide E to the rear of the shuttle-blocks F F. The stationary column I is attached to the framework A A at its lower part, and to it are fastened, on steps S S, the guides J J, on which the cross-head K slides. The cross-head is made in two parts. The back part, *t*, fig. 1, is made of wood, and the plate *v* of iron, having a slot 2, Figure 6, for the pitman to enter. To the iron plate *v* are cast the lubricating boxes L L, fig. 6, and also one half of the stirrup, indicated by *m*, in which is a depression to receive a section of a ball, *N*. The other half of the stirrup *o* is loose, and kept to its place on the iron plate *v* by means of a lug, cast upon the same, or any other convenient method. A box, *x*, passes through the ball, or section of ball, and through the stirrup, which keeps the saw held in said stirrup. In the side of the stirrup *m* are also inserted two set-screws *y g*, figs. 2 and 7, by which means the range of the saw at its lower extremity is regulated. By tightening the screw or bolt *x*, the saw is pressed firmly upon the section of the ball *N*, and thus a resting-surface is given, the saw keeping it steady constantly, and entirely obviating the difficulty of binding.

Having thus described my invention, what I claim, and desire to procure by Letters Patent, is—

1. The stirrup, with its fast and loose sides, holding in one side the section of a ball, and provided with set-screws for adjusting-purposes, all arranged and constructed as shown and described, and for the purposes indicated.
2. In connection with the stirrup, as shown, I claim the construction and arrangement of the various parts which constitute my muley-block, as described and for the uses indicated.

C. D. OLMSTEAD.
